CLAIM

The ornamental design for a grinder and fidget device as shown and described.

DESCRIPTION

FIG. 1 is a perspective view of a first side of the grinder and fidget device according to one or more additional examples of embodiments;

FIG. 2 is a plan view of the first side thereof;

FIG. 3 is a first elevation view thereof;

FIG. 4 is a second elevation view thereof, rotated 40 degrees from the view shown in FIG. 3;

FIG. 5 is a third elevation view thereof, rotated 80 degrees from the view shown in FIG. 3;

FIG. 6 is a perspective view of a second side thereof; and, FIG. 7 is a plan view of the second side thereof.

The ornament design which is claimed is shown in solid lines in the drawings. The broken lines in the drawings show portions of the grinder and fidget device which form no part of the claimed design.
